UNITED STATES PATENT OFFICE.

JAMES M. KING, OF BENEDICT, KANSAS.

END-GATE.

SPECIFICATION forming part of Letters Patent No. 377,680, dated February 7, 1883.

Application filed June 24, 1887. Serial No. 242,416. (No model.)

To all whom it may concern:

Be it known that I, JAMES M. KING, a citizen of the United States, residing at Benedict, in the county of Wilson and State of Kansas, have invented a new and useful Improvement 5 in End-Gates and Scoop-Boards, of which the following is a specification.

My invention relates to an improvement in end-gates and scoop-boards; and it consists in 10 the construction and arrangement of the parts of the same, which will be more fully hereinafter described, and particularly pointed out in the claims.

This invention is an improvement on Pat- 15 ents Nos. 197,783 and 314,509, dated, respectively, December 4, 1887, and April 22, 1879.

The object of my present improvement is to provide a combined end-gate and scoop-board which is constructed with closing gates pro- 20 vided with slotted ways, with which the sides of the scoop-board engage by means of trun- nion-pins when lowered for use. I attain this object by the construction illustrated in the accompanying drawings, wherein like letters 25 of reference indicate similar parts of the sev- eral views, and in which—

Figure 1 is a perspective view of a portion of a wagon-body with my improvement shown in connection therewith. Fig. 2 is a similar 30 view showing the scoop-board lowered for use. Fig. 3 is a perspective view of a portion of the scoop-board and end-gate when the scoop- board is lowered. Fig. 4 is an elevation of the end-gate shown open.

A indicates the wagon-body, the rear portion of which has two slotted standards, B, which are engaged by two vertical strips, C C, having suitable guide-irons, c, which engage with the slotted standards B. The guide-irons 40 c are formed with slots c', and are engaged by clamps c'', adapted to fit over the top of the wagon-body at this point. Through these clamps c'' a screw-bolt passes, which is engaged by an extended wing-nut, c'', and through the 45 medium of which the clamps c'' are secured firmly on the top portion of the wagon-body adjacent to the end-gate. Hinged to the stand- ards C are two gates, D D, which are adapted to open and close when desired. The inner 50 portion of the gates D are formed with circular-shaped slots d, which are bound by metallic bindings d'. The said slot d is continued in

the standard C, which at this point is also formed with metallic binding c''. The lower parts of the standards C are also provided with 55 elongated slots c'', which also have metallic bindings.

The scoop-board consists of a rectangular piece of suitable material having re-enforcing strips similar to the ordinary form of end-gate. 60 The scoop-board F has two trunnion-pins, f, at the lower sides thereof, which engage with the small elongated slots c''. The upper por- tions of said scoop-board are also provided with trunnion-pins f', which engage with the 65 slots c'' and d, formed in the standards or strips C and the gates D, respectively. The upper portion of the scoop-board F is provided with two hand-loops, f'', by which the same may be ad- justed in position. When the said scoop-board 70 is not in use, it is held in a vertical position, the upper trunnions thereof being situated in the slots c'' of the vertically-arranged slits C. The gates D are then closed against the said 75 scoop-board, a staple in connection with said scoop-board passing through one of the gates and is engaged by a hasp secured to the other end-gate. By this means it will be seen that the scoop-board is always held in a position ready for immediate use. 80

When it is desired to lower the scoop-board, the gates D are opened, and, being hinged to the standards or strips C, as shown, they are caused to bear against a portion of the wagon- body, and thereby project outwardly in the 85 same line as the sides of the said body. When the scoop-board F is lowered in the slots d, formed in a portion of the said gates, the said gates occupy an inclined position, and are held securely in said position by means of 90 the upper and lower trunnion-pins engaging with the slots or grooves hereinbefore de- scribed.

This form of end-gate, it will be understood, is intended for use in the transportation of grain 95 in bulk or of such other articles as are liable to fall out of the wagon. It will also be understood that the said scoop-board may be removed from connection with the end-gates when it is unnec- essary to use the same.

The novelty and utility of my improved de- vice being obviously apparent and apprecia- ble, it is unnecessary to further enlarge upon 100 the same herein.

Having thus described my invention, what I claim as new is—

1. The combination, with the end-gates and strips C, having slots formed therein, as set forth, of the scoop-board provided with trunnions adapted to engage with said slots, substantially as described.
2. In a combined end-gate and scoop-board, the combination of the gates D D, having the slots therein, as set forth, and the scoop-board F, operating in connection with said gates, substantially as described.
3. In combination with the strips C, the slotted guide-iron e, the clamps c², and the clamping-nut c³, substantially as described.
4. In combination with the strips C, the gates D, hinged thereto, the clamping devices to lock the strips to the wagon-body, the guideways or grooves in the gates D, and the scoop-board

hinged to the strips C, and having projections 20 or pins to work in the guide grooves or ways of the gates, as set forth.

5. In combination with the strips C, the gates D, hinged thereto, the adjustable clamps connected to the strips and engaging the wagon-bed, the guide grooves or ways in the gates, and the scoop-board hinged to the strips C, and having projections to engage the guideways and locking devices to lock the gates over the scoop-board. 25

In testimony that I claim the foregoing as my own I have hereto affixed my signature in presence of two witnesses.

JAMES M. KING.
